UNITED STATES PATENT OFFICE.

ARTHUR L. BROWN, OF MILFORD, PENNSYLVANIA.

KEYLESS PADLOCK.

1,286,521.

Specification of Letters Patent.

Patented Dec. 3, 1918.

Application filed July 11, 1918. Serial No. 244,456.

To all whom it may concern:

Be it known that I, ARTHUR LEROY BROWN, a citizen of the United States, residing at Milroy, in the county of Mifflin and State of Pennsylvania, have invented a new and useful Keyless Padlock, of which the following is a specification.

The device forming the subject matter of this application is a lock, adapted to be mounted on dinner pails and like structures, which call for a locking device which merely holds two parts together, as distinguished from a locking device which will resist the efforts of a burglar.

15 The invention aims to provide a padlock of the sort above mentioned which consists solely of two parts, to wit, a body and a shackle, one end of the shackle being connected with the body without using rivets 20 or other securing devices and without resorting to welding, the other end of the shackle and the body having integrally formed interlocking elements, whereby said other end may be held upon the body releasably.

25 It is within the province of the disclosure to improve generally and to enhance the utility of devices of that type to which the present invention appertains.

With the above and other objects in view, 30 which will appear as the description proceeds, the invention resides in the combination and arrangement of parts and in the details of construction hereinafter described and claimed, it being understood that, with- 35 in the scope of what is claimed, changes in the precise embodiment of the invention shown can be made without departing from the spirit of the invention.

In the accompanying drawings—

40 Figure 1 shows in elevation, a padlock constructed in accordance with the invention, parts being shown in section, Fig. 2 is a section on the line A—B of Fig. 1, looking in the direction of the arrow marked "2"; 45 Fig. 3 is a section on the line A—B of Fig. 1, looking in the direction of the arrow marked "3"; Fig. 4 is a top plan of the body, the shackle removed.

The device forming the subject matter of 50 this application preferably, but not necessarily, is fashioned from metal throughout, and includes a cup-shaped body 1, open at one side as shown at 2, the body including

a back 3 and a marginal rim 4. In the rim 4, a first opening 5 is formed, the constituent metal of the rim being bent inwardly, along one edge of the opening 5 to form an integral keeper 6. In the rim 4, a plurality of second openings 7 are formed. The invention comprises a U-shaped resilient 55 shackle 8, one end of which, as shown at 9, is threaded through the second openings 7, and is permanently held therein. The other end of the shackle is extended through the first opening 5 and is terminally provided 60 with an integral finger 10, adapted to engage the keeper 6, the keeper 6 and the finger constituting interlocking elements.

The end of the shackle 8 which carries the finger 10 may be inserted readily through 70 the opening 5, the resiliency of the shackle causing the finger 10 to interlock with the keeper 6. It is possible, however, to detach the finger 10 from the keeper 6 and to withdraw the free end of the resilient shackle 75 from the opening 5, by flexing the shackle 8 slightly.

The device forming the subject matter of this application obviously is made of two pieces only, and may be turned out at slight 80 expense, the structure not only being useful as a locking means, but, in addition, having utility, in that it may be used as an inexpensive advertising device, which may be given away.

Having thus described the invention, what is claimed is:—

A two-piece padlock comprising a body including a rim having a first opening, and provided with an integral keeper located at 90 one edge of the opening, the rim being provided with a plurality of second openings; and a spring shackle having one of its ends sinuously arranged in the second openings and permanently held therein by said sinuosity, the other end of the shackle being removably mounted in the first opening, and terminating in an integral angular finger 95 releasably engaged with the keeper.

In testimony that I claim the foregoing 100 as my own, I have hereto affixed my signature in the presence of two witnesses.

ARTHUR L. BROWN.
